WATCH TIMING APPARATUS

Thomas B. Gibbs, Chicago, Ill.

Application June 17, 1937, Serial No. 148,747

8 Claims. (Cl. 73—51)

The present invention relates in general to watch timing apparatus, and in certain respects it may be considered as an improvement on the watch timing apparatus disclosed in my prior application, Ser. No. 124,571, filed February 8, 1937. This prior application discloses a watch timer of the stroboscopic type, comprising a dial or reference member driven by 60-cycle commercial power, a speed-correcting mechanism controlled by a master watch, and means for illuminating the dial intermittently responsive to the ticks or beats of the watch under test.

While the above described apparatus has given good satisfaction, it has several objectionable features, among which may be mentioned the fact that it can only be used at points where regulated 60-cycle power is available. The stroboscopic principle, moreover, is not wholly suited to watch timing, as the beat frequency of a watch is so low that flicker is present, which is a strain on the eyes of the operator.

The object of the present invention therefore is to produce a new and improved watch timing apparatus which is free from the objectionable features of prior apparatus of this character.

More in particular, an object of the invention is to produce a watch timing apparatus which is not dependent on the frequency of the power supply and which can be arranged to operate from any commercial power source, whether A. C. or D. C.

A further specific object of the invention is to produce a watch timing apparatus in which the stroboscopic principle is dispensed with, and in which a new and improved arrangement is employed for comparing a watch under test with a master watch or other standard frequency source.

An incidental object is to provide a standard frequency generator using a master watch as a primary constant frequency source and having a 60-cycle or other desired frequency output with sufficient power so that the same can be used to operate a synchronous motor.

The foregoing and other features of the invention will be pointed out more in detail in the course of the description of the invention which follows, reference being had to the accompanying drawings, in which—

Fig. 1 is a front view of the mechanical part of the apparatus, referred to hereinafter as a timer;

Fig. 2 is a top view, on a larger scale, of the timer shown in Fig. 1, with the cover of the outside casing removed;

Fig. 3 is a side view of the timer, with the casing in section;

Fig. 4 is a partial section on the line 4—4, Fig. 2, showing the motor starting device;

Fig. 5 is a section on the line 5—5, Fig. 7;

Fig. 6 is a section on the line 6—6, Fig. 7;

Fig. 7 is a partial section on the line 7—7, Fig. 2;

Fig. 8 is a top view of the special tuning fork used in the constant frequency generator;

Fig. 9 is a side view of the tuning fork;

Fig. 10 is an end view of the tuning fork, taken from the right in Fig. 9;

Fig. 11 is a section through the crystal microphone unit associated with the tuning fork, taken on the line 11—11, Fig. 12;

Fig. 12 is another section through the crystal unit, taken on the line 12—12, Fig. 11; and

Fig. 13 is a circuit drawing showing in diagrammatic form the complete watch timing apparatus.

Referring particularly to Figs. 1, 2, and 3, the timer is mounted on a base 1, which may be a brass plate, provided with supports such as 2, preferably rubber. The reference character 3 indicates a casing, which may be of sheet metal.

The casing is provided with a cover 4 and is open at the bottom, where it fits closely around the base 1. Small brackets 5 may be provided, spot welded in the inside of the casing. These brackets rest on the base 1 to which they may be attached by screws to hold the casing in place.

In the front of the casing there is a curved opening or window 6 the edges of which are turned inwardly as seen in Fig. 3. Behind the window is a wide metal strip 7, shown in dotted lines in Fig. 1, and seen in Figs. 2 and 3. This strip 7 is secured to the inside of the casing at both ends, as shown in Fig. 2, and is spaced away from the casing except at its ends. The strip 7 serves to support a scale 8 in the proper position so that it can be seen through the window 6. The front of the casing also has mounted on it a starting switch 9.

Inside the casing and supported on the base 1 is a unit which comprises a synchronous motor, a dial, and an electro-magnetic device controlled by the beats of a watch being tested for rotating the dial. All of these parts are supported on a frame comprising the two horizontal plates 17 and 18 and the vertical plates 10, 11, and 12.

The plate 12 is held in position at the lower end by screws which are threaded into the plate 17, and plates 10 and 11 are secured at the lower end by means of similar but longer screws which pass through holes in the vertical plates and in the horizontal plate 18, and are threaded into

the plate 17. At the top the plates 10 and 11 are spaced apart by two rods or bars 13 and 14 to which the plates are attached by means of screws, as shown. Similarly, plates 11 and 12 are spaced apart by means of two bars 15 and 16, being held in position by screws which are threaded into the bars. This affords a substantial frame for rigidly supporting the rotating parts of the unit. The frame rests on the base plate 1 to which it may be attached by means of screws, as shown in Fig. 3.

The synchronous motor is similar to the motor shown in my co-pending application Ser. No. 124,571, filed February 8, 1937, except that it runs at higher speed and accordingly has fewer teeth in the armature. It comprises a shaft 20, armature 24, field magnet 28, and fly wheel 26. The shaft 20 is rotatably supported in the frame plates 10 and 11 by ball bearings 21 and 22. The armature 24 is pressed onto a hub 23 which may be secured to the shaft 20 by a set screw. The field magnet 28 is preferably of laminated construction, as shown, and is provided with a winding 31. The magnet is mounted on the frame plate 10 by means of two small bolts 29 and 30, there being two tubular spacers 32 and 33 inserted between the magnet and the frame plate 10 in order to position the magnet properly in alignment with the armature 24.

The fly wheel 26 is pressed onto a hub 25 which is rotatable on the shaft 20. A spiral spring 27 provides a flexible connection between the fly-wheel and the armature 24. The function of the fly-wheel is to enable the armature to fall into step at synchronous speed when the motor is started, and to this end it has the proper natural frequency of oscillation about the shaft 20 as determined by its weight and the stiffness of the spring 27.

The motor is started by means of a rack and pinion device which will now be described. On the outside of the frame member 10 there is secured a bracket 65, which has the downwardly-extending end portions 66 and 67. These end members are perforated to provide bearings for the rack member 68, seen in Figs. 2, 3, and 4. This rack member has a toothed section on its lower side which is adapted to engage with the pinion 74 mounted on the end of shaft 20. The rack member 68 is urged to the left, as seen in Fig. 4, by means of a coil spring 69. This spring is stretched between a bracket 70 attached to the casing and the downwardly-extending arm 71, which is part of the rack member 68. For the purpose of operating the rack there is provided a resilient rod 72 extending outside the casing and having attached to it a knob 73.

The dial is indicated by the reference character 62 and comprises a metal disk having three pointers, such as 80, spaced 120° apart, as shown in Fig. 1. The dial is mounted on a hub 61, Fig. 7, which in turn is carried on a shaft 52 to which it may be secured by a set screw. The shaft 52 is rotatably supported by means of two ball bearings 54 and 55 which are located at opposite ends of the sleeve or cylinder 53. The latter is threaded into an opening in the frame plate 12 and is locked in position by a nut 56. Between the hub 61 and the sleeve 53 is provided a cylindrical bushing 57, an ordinary washer 58, and a special spring washer 59, the latter having a number of radial arms or projections 60 which bear against the end of the sleeve 53. The bushing 57 is locked on the shaft 52 by means of a set screw, and the two washers accordingly con-

stitute a friction device for slightly limiting the freedom of rotation of the shaft 52. The amount of resistance offered to rotation may be adjusted by shifting the bushing 57 endwise on the shaft 52, which will change the tension in the spring washer 59.

As seen particularly in Fig. 3, the parts are so proportioned that the dial 62 rotates between the window 6 in the front of the casing and the scale 8. The diameter of the dial is such that it is wholly concealed behind the casing except for the pointers such as 80, one of which is always visible through the window, as shown in Fig. 1.

The electro-magnetic device by which the dial is controlled may now be considered, Fig. 7 being referred to in particular. This device comprises the armature 51 mounted on the dial shaft 52, and the electro-magnet 46 which is mounted on the motor shaft 20.

The shaft 20 extends through the ball bearing 22 to the left, and has rigidly secured to it the hub 35, which comprises a head portion to which the disk 43 is secured and a cylindrical portion of reduced size on which are mounted the slip rings 37 and 38. Between the slip rings and the hub there is a tube or sleeve 36 of insulating material. These parts may be held together by friction; that is, the tube 36 may be forced onto the hub and the slip rings should have a press fit on the tube 36.

Associated with the slip rings are two brushes 39 and 40 which are clearly shown in Figs. 6 and 7. Brush 39 is secured to the frame plate 11 by means of a screw 41 which is threaded into an insulated tubular rivet, as shown clearly in Fig. 7. This brush is in engagement with the slip ring 38. The brush 40 engaging the slip ring 37 is similarly secured to the frame plate 11 by means of the screw 42. As shown in Fig. 6, the brushes may be provided with offset lugs or tags for the attachment of conductors.

The electro-magnet 46 is preferably of laminated construction and is provided with a winding 47. The magnet is held in position between the legs of two U-shaped brackets 44 and 45 which in turn are attached to the disk 43 by means of screws as shown. As previously mentioned, the disk 43 is rigidly secured to the hub 35. The winding 47 is connected across the slip rings 37 and 38, as shown particularly in Figs. 3 and 7. As seen in Fig. 3, one end 49 of the winding is provided with a suitable insulating sleeve and is passed through a hole drilled in the disk 43, hub 35 and slip ring 37, and is soldered to the slip ring 38. The other end of the winding, indicated by the reference character 48 in Fig. 7, passes through a hole drilled in the disk 43 and in the hub 35, and is soldered to the slip ring 37.

The armature 51 is pressed onto the hub 50, which is secured to the shaft 52 by means of a set screw. The armature preferably has six poles, as shown clearly in Fig. 5, and should be accurately centered between the poles of magnet 46, with just enough clearance to permit of free rotation, except as limited by the friction device including the spring washer 59.

To facilitate the attachment of a cable for connecting the timer with the remaining apparatus, a terminal strip 90 may be provided, having terminals 91 to 94, inclusive. The brushes 39 and 40 may be connected to terminals 93 and 94, while the winding 31 of the motor may be connected to terminals 91 and 92. One end of the

winding is connected direct to terminal 91, and the other end of the winding is connected to terminal 92 through the switch 9. The cable may enter through an opening in the rear of the casting, and the four conductors of which it is composed may be connected to the terminals on the side opposite to where the brushes and winding 31 are connected.

Summing up all the foregoing, it will be seen that the timer includes the synchronous motor which is adapted to drive the shaft 20, carrying the magnet 46, there being slip rings mounted on the shaft to accommodate the magnet circuit, and the dial 62 which is rotatable against the resistance of the friction washer 59 and which is adapted to be rotated by the armature 51 cooperating with the electromagnet 46. The manner in which these parts operate will be described more in detail later on.

Reference will now be made to Figs. 8 to 12, 20 inclusive, for the purpose of describing the tuning fork which forms a component part of the constant frequency generator. The complete tuning fork, so-called, includes the fork proper, a driving magnet, a crystal pickup unit, a terminal strip, and a suitable base on which the parts are mounted.

The fork comprises the tines 104 and 105 and the heel 106, and may be cast in the form shown, preferably of a special ferrous alloy having such characteristics that the frequency of the fork is substantially independent of temperature changes over a wide range. The tines 104 and 105 are provided with weights 107 and 108, respectively, for convenience in tuning the fork at the factory. These weights need not be adjusted afterwards, except under unusual circumstances.

The base 100 for supporting the fork and other parts is preferably a casting in the form shown, and has a pedestal 102 at one end on which the fork is mounted. The top of the pedestal has a shallow groove or recess to receive the heel 106 of the fork, which is held securely in place by means of two screws 103.

The drive magnet is indicated by the reference character 113 and is preferably of laminated construction. The magnet has a winding 117 and two pole pieces 114 and 115. The pole pieces are secured to the core by means of small screws which also serve to hold the laminations together at the ends. The magnet is supported by means of two small posts 109 and 110 which are part of the base, and is rigidly secured to these posts by means of bolts 111 and 112.

The pickup device is a crystal microphone unit 121, which is similar to the crystal unit disclosed in my prior application, Ser. No. 124,570, filed February 8, 1937. The so-called crystal which constitutes the operative element of the microphone unit comprises two square sheets or plates 136 and 137, Fig. 12, of Rochelle salt, cemented together with a layer of tin foil 138 between them. There is also a layer of foil 134 on one side and a layer of foil 135 on the other. There is a thin strip of brass 150 assembled next to the central foil 138, and underneath the foils 134 and 135 are assembled thin brass strips 139 and 140, respectively. The brass strips 139 and 140 are directly opposite one another, and their ends are brought together and are soldered to the terminal strip 141. The brass strip 150 is soldered to a terminal strip 151. At one corner of the assembled crystal there is cemented a member 142, to which is attached a short pin or rod 143.

The crystal is contained in a sealed receptacle

comprising the two metal plates 130 and 133 and the rubber rings 131 and 132. The construction of the receptacle is clearly shown in Figs. 11 and 12. The crystal is supported by six rubber blocks such as 152, three above and three below. The terminal strip 151 passes out between the rubber rings 131 and 132, as seen in Fig. 11. The terminal strip 141 is bent, as shown in Fig. 12, and is assembled between the ring 132 and the metal plate 133. It is cut off short enough so that it does not pass outside the receptacle. The pin 143 passes out through an opening in plate 133, this opening being provided with a soft rubber bushing surrounding the pin 143. The receptacle with the crystal contained therein is subjected to compression after assembly, and the plates 130 and 133 are then secured together by means of four tubular rivets 144-147. Thus the terminal strips are clamped in position and the crystal is resiliently supported at three corners by the rubber blocks 152, which are compressed between the plates 130 and 133.

The complete crystal unit 121 is mounted adjacent the tuning fork on a support 120, to which it is secured by means of four screws such as 148, 25 as seen in Figs. 8 and 9. The support 120 may be cast as part of the base 100. The pin 143 is cut off to the proper length so that when the unit 121 is in position the pin will just reach the tine 105 of the fork. A spot on this tine has previously been tinned, so that the end of the pin is readily secured to the tine by a drop of solder.

A terminal strip is indicated by reference character 161, and comprises a flat strip of fiber 161 and four terminal lugs 162-165. The strip is secured to the base 100 by means of two screws 166 and 167. Two tubular spacers 168 and 169 may be inserted between the strip and the base. 35 The terminal 151 of the crystal unit may be connected to terminal lug 162. The other terminal 141 is grounded on the frame, and the frame is therefore connected to lug 163 by a short conductor secured under the head of screw 167, unless the base is otherwise grounded. The terminals 162 and 163 therefore are the output terminals for the crystal unit. The winding 117 may be connected to terminals 165 and 164.

The tuning fork is driven by impulses generated responsive to the ticking of a master watch, as will be explained presently, but for various reasons the frequency of the fork must be considerably higher than the beat frequency of the watch, which is five cycles per second. 50 For one thing, it is extremely difficult, if not impossible, to amplify a five-cycle alternating current and produce an output current suitable for operating a synchronous motor. The equipment required is very expensive, and the results obtained even with the best apparatus available are unsatisfactory. Another consideration that renders a higher frequency essential is the hunting that is always present in a synchronous motor. With a very low frequency, on the order of five cycles per second, the number of poles on the motor is so low that the hunting makes a watch timing apparatus inoperative for all practical purposes. The frequency must not be so high, however, as to make it impracticable to 55 drive the fork from the beats of the master watch, and it must of course be an exact multiple of the beat frequency. Experiments have shown that the foregoing conditions are met satisfactorily if the fork is tuned to a frequency of 60 cycles per second. The fork is so designed

that its natural frequency is very close to 60 cycles, and it is then tuned exactly by adjusting the weights 107 and 108.

Referring now to Fig. 13, the timer and tuning fork, already described in detail, are shown diagrammatically within the dotted enclosures labeled T and F, respectively. The timer is a unit by itself, as shown in Figs. 1 to 7, inclusive. The tuning fork is also a complete unit, but is preferably mounted along with other items in a large casing which may be referred to as a power cabinet. These other items include the amplifier A1, the voltage regulator VR, the power amplifier PA, the power supply unit R, and the amplifier A2. As the power cabinet may be of any suitable design and construction, such as is commonly used to house amplifiers, radio sets, etc., it has not been shown.

The microphone 200, used for picking up the beats from the master watch, may be mounted in the power cabinet in a shockproof compartment, as shown in my copending application Ser. No. 124,571, filed February 8, 1937. This microphone, as well as the test watch microphone 260, is preferably of the type shown in my Patent No. 2,175,021, granted October 3, 1939. This latter application shows the microphone complete with stand and cord for connecting it up to an amplifier. If desired, the stand may be enlarged so as to include the compartment for the master watch microphone; and if this is done, a single two-conductor cord will suffice for connecting both microphones to the power cabinet. This cord, it will be understood, should be provided with a metallic sheathing in order to shield the conductors and ground the casings of the microphones.

The amplifier A1 comprises a type 57 pentode 202, a type 6C8G double triode 203, and a type 885 thyratron 204. The tubes mentioned have been used in practice and operate very satisfactorily, although it will be understood that other types of tubes which are on the market could also be used.

The circuit connections for the pentode 202 are similar to those shown in my prior application hereinbefore referred to, but may be described briefly nevertheless. One side of the crystal unit in the microphone 200 is connected to the casing and thence to ground, as shown, and the other side is connected over a conductor 201 to the grid of the pentode. The conductor 201 should be shielded as previously mentioned. The plate of the tube is connected to the plus B lead through a resistor 210. The suppressor grid, the grid next to the plate, is connected to the cathode, and the latter is connected to ground through a resistor 207, which is an arrangement commonly employed to provide a negative grid bias. The resistor 207 is shunted by a by-pass condenser 208. The screen grid of the tube is connected to the plus B lead at a point between the two bleeder resistances 270 and 271, so that the voltage at the screen grid will be somewhat less than the voltage at the plate. The control grid is connected to ground through a high resistance grid leak 206.

The plate circuit of the pentode 202 is coupled to the grid of the left triode of tube 203 by means of a condenser 211. The tube 203 constitutes in effect two ordinary triodes with conventional circuit connections which need not be described in detail. The plate of the left-hand triode is coupled to the grid of the right-hand triode through a condenser 213 and the potentiometer 212. The

latter functions as a grid leak for the grid of the right-hand triode and also as a volume control.

The plate circuit of the right-hand triode of the tube 203 includes the resistor 214 and is coupled to the control grid of the thyratron 204 by means of the condenser 215. This control grid is provided with a negative potential over a conductor 257 and through the resistance 216, sufficiently to normally bias it to cut off condition.

10 The plate circuit of the thyratron includes the winding 117 of the tuning fork drive magnet 116 and the condenser 217, the latter being shunted by the high resistance 218. The condenser is therefore normally discharged, and is in condition 15 to charge over a circuit including the thyratron 204 and the winding 117 whenever the tube has its grid bias lowered enough to enable it to pass current.

15 The voltage regulator VR includes a type 6C8G 20 double triode with the circuit connections as shown. The left-hand triode functions as an amplifier, while the right-hand triode functions as a voltage regulator. The crystal unit 121 of the pickup device at the tuning fork is resistance 25 coupled to the grid of the left-hand triode. One terminal of the crystal unit is connected to ground, as shown, while the other terminal is connected to ground through the two resistors 219 and 220 in series. These resistors may have a 30 value of 150,000 ohms each. The junction of the two resistances is connected to the grid of the left-hand triode.

20 The plate of the left-hand triode is connected to the plus B lead through a resistor 221, and the plate circuit is coupled to the grid of the right-hand triode by means of a condenser 223 and a resistor 224. The condenser 223 may have a capacity of .25 mf., while the value of the resistor 224 should be very high, preferably about 5 meghoms. The junction point 0 between the condenser 223 and the resistor 224 is connected to ground through the grid leak 225, which may have a value of 500,000 ohms.

25 The plate circuit of the right-hand triode is 45 connected to the plus B lead through a resistor 226 of about 50,000 ohms and a filter circuit comprising the inductance 227 and the condenser 228. The capacity of the condenser and the value of the inductance are such that the filter circuit is 50 sharply turned to 60 cycles. The filter circuit is 55 coupled by means of a condenser 229 to the output lead 262 leading to the power amplifier.

60 The power amplifier comprises an ordinary triode 240 and two type 6N7 double triodes 241 and 242. The output lead 262 coming from the voltage regulator VR is coupled to the grid of the triode 240 by means of a potentiometer 235, which constitutes an adjustable grid leak and is used as a voltage control. The plate circuit of the triode 240 is coupled push-pull to the grids of the double triodes 241 and 242 by means of the transformer 243. It will be observed that the two grids of tube 241 are connected in parallel and that the two plates are also connected in parallel, the same being true of tube 242. The plate circuits of tubes 241 and 242 are coupled by means of the transformer 244 to the output leads 263 and 264, which lead to the timer T. At the timer these conductors lead to the winding 31 of the synchronous motor, the circuit including a contact on the switch 9.

65 The amplifier A2 is similar to the amplifier A1 and hence is not shown in detail, being represented merely by a rectangle in which the outgoing and incoming conductors are terminated.

The amplifier A2 may in fact be exactly like the amplifier A1 except that the condenser corresponding to the condenser 217 and the resistor corresponding to resistor 218 do not have the same values. This will be explained later on in describing the operation of the equipment. The two output leads 267 and 268, which correspond to the output leads 265 and 266, respectively, of the amplifier A1, extend to the timer T and through the slip rings 37 and 38 to the winding 47 of the electromagnet 46. One side of the circuit includes a contact of the switch 9.

As shown in Fig. 13, the equipment is arranged to be operated from some alternating current commercial power source, and to this end a plug P may be provided which can be inserted in any convenient socket on the premises. The reference character S represents a main switch by means of which the power circuit is extended from the plug through to the primary winding 251 of the transformer 245.

The transformer 245 is included in the power supply unit R and has a number of windings, the function of which will be mentioned briefly. The winding 250 supplies current to the heaters of the various tubes shown throughout the drawings including those in the two amplifiers A1 and A2 and in the voltage regulator and the power amplifier. The heater circuits have not been drawn in, but it will be understood that each heater circuit which is labeled X—X is in practice connected to the terminals X—X of the winding 250, a suitable resistor being included in the heater circuit of tube 202 in order to limit the current to about one ampere.

The main rectifier tube 253 is connected for full wave rectification and has the function of supplying plus B potentials to the various tube circuits. The two plates of the tube are connected to the opposite terminals of the winding 248. The midpoint of this winding is grounded and constitutes the negative terminal of the power supply unit. The cathode of the tube is supplied with heating current from the winding 249 of the transformer and is connected through a suitable filter to the various plus B leads, as illustrated. The highest voltage is supplied to the lead 259 over which power is supplied to the plates of the tubes 241 and 242 of the power amplifier. A somewhat lower voltage is supplied over the conductor 254 to the plate of the amplifying triode 240, and a still lower voltage is supplied over leads 255 and 256 to the two amplifiers A1 and A2 and to the plates of the tube 205 in the voltage regulator VR.

The rectifier tube 252 is also connected for full wave rectification and is provided for the purpose of supplying negative grid bias potential to the thyratrons in the amplifiers A1 and A2. The cathode of the tube is heated by means of the winding 247 of the transformer 245 and is connected to ground. The two plates of the tube are connected to the opposite terminals, respectively, of the winding 246 of the transformer 245. The midpoint of this winding constitutes the negative terminal of the rectifier and is connected through a suitable filter circuit to the conductors 258 and 257. The conductor 257 is connected through the resistor 216 to the grid of the thyratron 204 in the amplifier A1, and the conductor 258 is similarly connected in the amplifier A2.

The apparatus having been described, its operation in timing watches will now be explained. It may be assumed that a master watch which

has been previously regulated to keep correct time is clamped to the microphone 200. The master watch should be a five-beat watch and should be adjusted so that the successive beats are evenly spaced. A high grade watch is obviously desirable, and the more perfect its regulation the better, but it need not be regulated for various positions.

The first step on starting up the apparatus is 10 to insert the plug P, Fig. 13, in a convenient socket connected to commercial A. C. power, after which the switch S may be closed. As a result, power is supplied to the unit R, and the latter functions to supply heating current to the 15 various tubes and to supply power for the plate circuits of the tubes over the plus B leads. The requisite negative potential is also placed on the grid bias leads 251 and 258. The amplifiers are thus rendered active and ready to perform 20 their respective functions.

The master watch being in position on the microphone 200, at each beat or tick of the watch, a mechanical shock is transmitted to the crystal element in the microphone, in response to which the crystal element generates an electrical impulse, which is transmitted over the conductor 201 to the grid of the amplifying pentode 202. The impulse is amplified at the pentode 202 and is passed on through the condenser 211 to the grid of the left triode of the double triode 203, where it is further amplified. The plate circuit of the left triode being coupled to the grid of the right triode through the condenser 213, the impulse is amplified once more, 35 and is then transmitted through the condenser 215 to the grid of the thyratron 204, where it reduces the normal negative grid bias enough so that the tube can fire. The action is not as simple as this, in reality, but it is well understood and hence it will not be necessary to go 40 into details.

When the thyratron fires, or starts to pass current, the condenser 217 charges over a circuit which may be traced from ground by way of the cathode and plate of thyratron 204, winding 117, and condenser 217 to the plus B lead 255. The condenser 217 charges rapidly over the above circuit and as a consequence the current flow through the tube 204 falls rapidly toward a value determined by the high resistance 218, which extinguishes the tube. The condenser then discharges through the resistance 218 in preparation for charging again the next time the thyratron fires.

The charging current of the condenser flows through the winding 117 of the tuning fork drive magnet 116, as per the circuit above traced, and accordingly the magnet is energized, attracting the tines 104 and 105 of the tuning fork and pulling them apart. The energization of the magnet 116 is of very short duration. When the tines are released they start vibrating at the natural fork frequency, or 60 cycles per second. The next time the condenser 217 charges the magnet 116 is energized again, giving another pull to the fork tines. This action is repeated responsive to each beat of the watch, or five times per second, and the fork is very shortly brought up to full amplitude of vibration.

It is essential that the duration of the impulses delivered to the magnet 116 by the charging of the condenser be properly related to the fork frequency in order to secure a satisfactory drive. The magnet is effective to drive the fork only when the tines are moving away from each

other, or toward the magnet poles, and as the frequency of the fork is 60 cycles per second, this movement takes place in $\frac{1}{120}$ of a second. It has been found by experiment that excellent results are secured if the impulses delivered to the fork are about $\frac{1}{4}$ of this interval, and the capacity of condenser 217 is therefore so related to the impedance of winding 117 that the condenser will charge up enough to extinguish the thyratron in about $\frac{1}{480}$ of a second.

The winding 117 and the condenser 217 are therefore so designed as to give the proper length of drive impulses, and this may be done before taking into consideration the proper response of the thyratron to the watch beats. This latter is taken care of by properly regulating the value of the resistance 218. This resistance should be low enough so that it will substantially discharge the condenser 217 between watch beats, or in $\frac{1}{5}$ of a second, and it should be high enough so that the condenser cannot discharge fast enough to permit the thyratron to fire a second time responsive to the same watch beat.

It will be seen now that at each beat of the master watch an impulse is produced which is amplified by the tubes 202 and 203 and which is effective to trigger the thyratron and permit the condenser 217 to charge through the tube and the winding 117 of the drive magnet. The impulses thus transmitted to the drive magnet, being derived from the master watch, have a frequency of exactly five per second, or $\frac{1}{12}$ of the fork frequency, and therefore are in step with the fork and serve to maintain it in operation. This is not to say that the fork must have a frequency of exactly 60 cycles per second, although it is tuned as nearly to that frequency as possible. A variation of as much as three or four minutes per day in fork frequency is permissible. When the fork is slightly off, either fast or slow, a correction takes place five times per second, or at each drive impulse.

The exact manner in which the correction takes place is difficult to determine, although careful observations have been made. If the fork has exactly the proper frequency, the drive impulse is apparently delivered as the tines are nearly separated the maximum extent and is terminated slightly after the tines come to rest before starting to approach each other. Now, if the fork is too fast it will gain on the drive impulses, and the tines will start to approach each other on each drive impulse enough before the impulse is completed so that it can exercise a slight retarding effect. On the other hand, if the fork is too slow, the drive impulses will gain on the fork, and each drive impulse will come in at a time when it can deliver more power to the fork than it could if the fork had exactly the right frequency, with the result that the fork is accelerated. This explanation of course implies that the drive impulses have considerably more power than is necessary to drive the fork when exactly in tune, which is the case. It may be mentioned also that if the fork is considerably off as to its frequency, although not enough to prevent it from running in step with the master watch, its amplitude will be reduced. This, however, is prevented from having any deleterious effect by the voltage regulator, as will be presently explained.

The vibrations of the tuning fork are transmitted to the crystal microphone 121 by the pin 143, as is evident from Fig. 8, and the microphone generates a 60-cycle alternating current in a cou-

pling circuit including resistances 219 and 220, whereby alternating potentials are applied to the grid of the left triode of the double triode tube 205. As a result, the plate current fluctuates and the voltage on the plate of the left triode rises and falls. This causes the condenser 223 to charge and discharge in series with the resistor 225, and alternating voltages are produced at the point 0 in the condenser circuit. These potentials vary in amplitude, depending on the amplitude of the voltages applied to the grid of the left-hand triode, which in turn depend on the tuning fork amplitude, and it is the function of the right-hand triode to limit the effect of both the positive and the negative half waves and maintain a uniform output within certain limits independent of the strength of the impressed voltages.

The effect of the negative potentials is limited by proper adjustment of the grid bias of the right-hand triode. This grid bias is adjusted so that with a negative half wave of the minimum strength some current will still flow through the tube; but if the signal strength is increased somewhat, producing voltage changes at the point 0 of higher amplitude, the negative half waves will bias the tube to cut off, and no current will flow during the peak values of such negative half waves.

The positive half waves are limited as to their effect by means of the resistor 224, which is in series with the grid. This resistance has no effect during the negative half waves, as the grid is drawing no current, but when the grid swings positive it draws current through the resistor 224. The resistor 224 is very high, being about 5 megohms, and consequently the drop is so high that the potential on the grid can rise only an infinitesimal amount. The result is that no matter what amplitude the positive half wave voltages at the point 0 have, the grid can never become more than a fraction of a volt positive, and the current through the tube is definitely limited to what can flow with this grid potential.

It will be seen therefore that the right triode of tube 205 operates as a voltage regulator and supplies a 60-cycle output of substantially uniform voltage independent of the amplitude of the tuning fork. When the fork has the minimum amplitude for which the circuit is adjusted, the output of the right triode of tube 205 will be approximately a sine wave, but with increasing amplitudes the voltage-regulating characteristics come into play and the output has a flattened wave formation. In order to correct this, the plate circuit includes a resonant circuit comprising the condenser 228 and inductance 227 which is tuned to 60 cycles per second. This tuned circuit is coupled to the output lead 262 through a condenser 229, and the voltages on this output lead are of excellent wave form, approximating a sine wave, and are of substantially uniform voltage, irrespective of varying fork amplitudes within wide limits.

The power amplifier comprising the triode 240 and the power tubes 241 and 242 functions in known manner, receiving 60-cycle alternating potentials from the output lead 262 of the constant frequency generator and delivering 60-cycle alternating current to the output leads 263 and 264.

There are two controls which are used in adjusting the equipment whose operation has been explained up to this point. The potentiometer 212 is used as a volume control to adjust the

amplifier A1 in order to secure a regular firing of the thyratron 204 responsive to the beats of the master watch. The potentiometer 235 is used to adjust the output voltage of the power amplifier to the desired value. When once adjusted these controls need no attention for long intervals.

The switch 9 may now be closed, thereby bridging the field winding 31 of the synchronous motor in the timer T across the output leads 263 and 264. The motor is started by pulling out the knob 73 and releasing it. When the knob is pulled out, the rack 68 is moved to the right, as seen in Fig. 4, and tension is stored in the spring 69. At the same time the teeth on the rack engage the pinion 74 and rotate the shaft 20. This rotation, however, is merely incidental to the starting operation. When the knob is released, the spring 69 draws the rack rapidly to the left and rotates the pinion 74 in the opposite direction. This spins the armature 24 rapidly, at a speed which is somewhat higher than synchronous speed. When the rack reaches its left-hand position as shown in Fig. 4, the teeth are disengaged from the pinion and the armature is allowed to run free. It therefore slows down gradually to synchronous speed at which point it falls into step with the assistance of the flywheel 26.

If the teeth of the rack do not properly engage the pinion when the knob 73 is pulled out, the rack will rise slightly at the right-hand end, as seen in Fig. 4, such action being provided for by the resiliency of the rod 72 and by the enlarged opening in member 66 which provides a little play above the rack. The spring 69 pulls slightly downward on the rack which insures that the teeth will engage when the knob is released, if not before.

The synchronous motor in the timer T is now being driven by the master watch through the intervening apparatus including the beat amplifier A1, the tuning fork F, the voltage regulator VR, and the power amplifier PA. This apparatus serves to convert the five-cycle beat frequency output of the microphone 200 into an amplified 60-cycle current having power enough to run the motor. The motor runs at five revolutions per second, and to this end the armature 24 is provided with twenty-four teeth. By means of shaft 20 the motor rotates the magnet 46 in a counter clockwise direction, as viewed from the front of the timer. The dial 62 is stationary.

A watch to be tested may now be clamped to the microphone 260. It may be assumed that the watch is a five beat watch. The microphone responds to the watch beats and generates impulses which are amplified by the amplifier A2 and are effective to control the thyratron in this amplifier in the same manner as described in the case of thyratron 204 in amplifier A1. The plate circuit of the thyratron includes the two output leads 267 and 268, corresponding to leads 265 and 266 of amplifiers A1; and when the thyratron fires the condenser which corresponds to condenser 217 charges over a circuit which includes the cathode and plate of the thyratron, lead 267, winding 47 of magnet 46, switch 9 (now closed), lead 268, and the condenser. As soon as the condenser becomes substantially charged, current flow is reduced sufficiently to extinguish the thyratron, and the condenser then discharges through a resistance corresponding to resistance 218. The action is the same as described in the case of thyratron 204.

and condenser 217, except that the capacity, impedance, and resistance values are so chosen that the impulses delivered to the magnet 46 are much shorter than those delivered to the drive magnet 116 of the tuning fork. Impulses not over $1/1500$ of a second in duration give good results.

It should be recalled now that the magnet 46 is rotating in a counter clockwise direction at a speed of five revolutions per second. The first impulse received will come in at a time when the magnet 46 is in some random position relative to the armature 51. If the magnet and armature are in the position in which they are shown in Fig. 5, no rotation of the armature will ensue; but if the magnet is in such a position that the magnet poles are not in alignment with a pair of armature poles, the nearest pair of armature poles will be attracted and the armature will be rotated. This rotation is opposed by the resistance developed at the friction device including the spring washer 59, and by the inertia of the armature 51 and dial 62, and the adjustment is such that, having regard to the very short duration of the impulses, the maximum amount of rotation that can take place responsive to a single impulse is about four or five degrees. Several impulses may be required therefore in order to position the armature 51 with relation to the effective position of the rotating magnet 46. When this has been accomplished no further rotation of the armature 51 will take place, if the watch being tested is keeping correct time with respect to the master watch, as the magnet 46 will be in the same position relative to the armature each time the magnet is energized. This will be clear from the fact that the magnet 46 rotates five times per second and from the further fact that the watch being tested is a five beat watch.

From the foregoing it will be evident that the operator viewing the apparatus from the front, Fig. 1, will usually observe a movement of the pointer 80 in one direction or the other immediately upon placing the test watch on microphone 260. This movement is of course recognized as being due to the initial positioning of the armature relative to the rotating magnet and is disregarded. If the test watch is keeping correct time, no further movement of the pointer will occur, and the operator knows from this that the watch is correct.

Assuming now that the test watch is running too slowly, the rotating magnet will gain on the impulses which it receives from the test watch and will rotate slightly more than a complete revolution between successive impulses. As each impulse is received, therefore, the magnet will be in a slightly advanced position where it can exert a pull on the armature, tending to rotate the dial and pointer 80 in a counter clockwise direction. The pointer 80 will therefore move gradually to the left as seen in Fig. 1, indicating to the operator that the test watch is running slow.

Assuming, on the other hand, that the test watch runs too fast, the impulses delivered to the rotating magnet 46 will gain on the magnet, which will make somewhat less than a complete rotation between successive impulses. As each impulse is received, therefore, the magnet will be in a retarded position relative to the armature and will rotate it in a clockwise direction, moving the pointer 80 to the right, as seen in Fig. 1.

Such movement of the pointer indicates to the operator that the test watch is too fast.

The amount by which the pointer drifts to the right or left within a given time determines how much the test watch is too fast or too slow. In order to facilitate the timing operations, the scale 8 is preferably laid out with such a spacing between divisions that if the scale were continued around a complete circle there would be 96 scale divisions. Each scale division will then correspond to a gain or loss of three seconds per day on a test of one minute duration. In timing a watch the operator notes the position of the pointer 80 after the initial positioning movement has taken place and then allows the apparatus to run for one minute, when the new position of the pointer is noted. If the pointer moves four scale divisions during the one minute interval, this means that the test watch is twelve seconds per day fast or slow, depending on the direction of the movement.

The error in seconds per day, which corresponds to a drift of any number of scale divisions during a one minute test, may be calculated from the proportion

$$n:dpm=x:86400$$

in which n =drift in scale divisions, dpm =rotational speed of magnet 46 measured in scale divisions per minute, x =error in seconds per day, and 86400=number of seconds in one day.

For the case of the particular timing apparatus disclosed herein the quantity dpm is equal to 28800 ($5 \times 60 \times 96$), and the proportion may be reduced to an equation for x in the form

$$x=3n$$

From this equation it will be seen that if the drift in one minute is one scale division, for example, the error is equal to three seconds per day.

Six beat watches may be tested in the same manner as five beat watches. The apparatus operates the same except that the impulses received by magnet 46 will have a frequency of six per second instead of five per second and will gain on the rotating magnet at the rate of one-sixth rotation per impulse. The armature 51 has six poles, and the magnet 46 will therefore lag behind each impulse a distance of exactly one pole spacing, and will operate on successive pairs of poles instead of on the same pair each time.

The apparatus has been shown herein as operating from a source of commercial alternating current, but obviously will operate from direct current. If a suitable source of direct current is available the power supply unit R can be dispensed with.

The timer disclosed herein has numerous advantages and is to be highly recommended, but is not absolutely essential. Other forms of timing apparatus can be used if desired. For instance, the timing apparatus described in my pending application Ser. No. 124,571 may be used. When this is done, the motor is driven by the master watch through the medium of the apparatus disclosed in the instant application, and the correcting mechanism is omitted entirely. The complete timing apparatus will then consist of the constant frequency generator as disclosed herein, the motor and dial of my prior application referred to, and the dial-illuminating means responsive to the beats of the test watch as also disclosed in my prior application. This makes a very simple and economical equipment suited

to the use of those desiring the stroboscopic type of apparatus.

The invention having been described, that which is believed to be new and for which the protection of Letters Patent is desired will be pointed out in the appended claims.

I claim as my invention:

1. In a device for timing watches of different beat frequencies, an electromagnet, an armature operatively related to said electromagnet and having a number of poles bearing a predetermined relation to the beat frequency of one watch, means for producing relative rotation between said magnet and armature at a speed bearing a predetermined relation to the beat frequency of the other watch, means responsive to the beats of the watch being tested for periodically energizing said magnet, and an indicator controlled by said armature.

2. In a timing device, a casing having an arcuate window therein, a rotatable member mounted inside said casing and having a plurality of indicators adapted to be viewed through said window, said indicators being angularly spaced the proper distance so that one indicator is always visible, a scale associated with said window, and means within the casing for rotating said member at a speed dependent on the amount by which the rate of a device being tested departs from a predetermined rate.

3. In a device for timing periodic impulses, an arc-shaped scale, a rotatable member having a plurality of sections one of which is always associated with said scale, an armature for rotating said member, said armature having at least as many sets of poles as said member has sections, a magnet cooperating with said armature, means for rotating said magnet at constant speed, and means responsive to said impulses for causing momentary energizations of said magnet.

4. In a device for timing periodic impulses, indicating means comprising cooperating fixed and rotatable members, the rotatable member having a plurality of equivalent angularly spaced parts, an armature for rotating said rotatable member and having a plurality of sets of poles, a magnet adapted to cooperate with a random pole set, means for rotating said magnet at constant speed, and means responsive to said impulses for causing momentary energizations of said magnet.

5. In a device for timing periodic impulses, a magnet, means for rotating said magnet at a constant speed, a normally stationary armature having a plurality of sets of poles adapted to cooperate with the poles of said magnet, means responsive to each impulse for causing a momentary energization of said magnet, the rotational speed of said magnet being such that it cooperates with successive adjacent sets of armature poles on successive energizations, and an indicator moved by said armature in one direction or the other depending on whether the impulse frequency is fast or slow.

6. In a watch timing apparatus, in combination, an electromagnet, means for rotating the electromagnet at a constant speed, an armature positioned within the field of the electromagnet to be controlled thereby, a tick responsive device adapted to respond to ticks of a watch to be tested, and an electrical circuit controlled by the tick responsive device and connected to momentarily energize the electromagnet at intervals corresponding to the ticks, whereby the position of

the armature is controlled by the ticks to give an indication of the rate thereof.

7. In apparatus of the character described, in combination, a rotatable member, an electromagnet carried by the rotatable member, means for periodically momentarily energizing the electromagnet, an armature mounted substantially concentrically with the rotatable member and within the field of the electromagnet, and means for frictionally normally maintaining the armature at rest, the friction being not so great as to prevent the armature from moving into alignment with the electromagnet when it is momentarily energized but being sufficient to prevent overrunning of the armature upon the termination of the momentary energization.

8. In apparatus of the character described, in combination, an electromagnetic structure in-

cluding two parts, one part comprising an electromagnet and the other part comprising an armature cooperating with said electromagnet, means for supporting said parts for independent rotation on a common axis, means for periodically momentarily energizing said electromagnet, means for rotating one of said parts at a predetermined constant speed, and means for frictionally normally maintaining the other part at rest, the friction being not so great as to prevent the said frictionally held part from moving into alignment with the other part when the electromagnet is momentarily energized but being sufficient to prevent overrunning of the said frictionally held part upon the termination of the momentary energization.

THOMAS B. GIBBS.
